G. R. WELCH

VAPORIZER

Filed Feb. 25, 1924

FIG. 1

FIG. 2

FIG. 3

George R. Welch -- INVENTOR.

BY

Stanley M. Udall
ATTORNEY.

UNITED STATES PATENT OFFICE.

GEORGE R. WELCH, OF DETROIT, MICHIGAN, ASSIGNOR, BY MESNE ASSIGNMENTS, TO HANDY GOVERNOR CORPORATION, OF DETROIT, MICHIGAN, A CORPORATION OF MICHIGAN.

VAPORIZER.

Application filed February 25, 1924. Serial No. 694,995.

The object of this invention is to automatically compensate for the variation in temperature of the exhaust gases. The great problem in a vaporizer of the type described is that if a sufficient area is provided for low speed operation the area at high speed is altogether too big and vice versa. The invention is shown applied to a four cylinder engine.

5

10 Figure 1 shows a cross sectional elevation of a combined inlet and exhaust manifold showing vaporizing means for the mixture.

15 Figure 2 is a cross sectional elevation on the plane 2—2 of Figure 1.

20 Figure 3 is a horizontal cross sectional elevation on the plane 3—3 of Figure 1.

A is the mixture entrance which admits the explosive mixture to the inlet manifold. 25 The inlet manifold consists of two branches B and C, which communicate with two inlet ports D and E. The inlet ports D and E are also connected by the dependent passage K. This dependent passage K is cast integral with the exhaust manifold G, being cored therein, as shown in Figure 1.

The inlet manifold is provided with four exhaust ports F F F F and the exhaust outlet H. The dependent passage K is so located as to be swept by the exhaust from each of the four exhaust ports. The passage K is preferably of substantially the same area as the passage B, and it should not be smaller than 40% of the passage B in order that it can function as desired. In Figures 2 and 35 the lips J J are shown surrounding the inlet ports D and E.

40 Operation: Assuming that the mixture is being drawn in through the inlet port D, an explosive mixture enters at A, and a portion flows through B directly into D. Another portion is from K to D. The portion flowing through B is relatively cold, and wet fuel will be deposited on the walls of the inlet manifold at this point. This fuel will be prevented by the lips J from entering the mixture entrances D.

45 When the inlet valve connected to the inlet port E opens, the wet fuel which was prevented by the lips J from entering the port G, flows down the dependent passage K, being drawn down by the air drawn from K into the port E. The wet fuel which is drawn down into K is thus rapidly vaporized.

50 It thus follows that the mixture drawn in

at E will consist of a mixture of finely atomized fuel and cold air, and the coarser particles of fuel which are being vaporized in K, together with highly heated air. At high engine speed, when the pulsations due to the inlet valves opening are frequent, the heating value of the dependent passage K will be reduced and therefore the heating effect of the vaporizer will be lessened automatically without any valves or gear of any kind.

60

65 On the other hand, when the engine is running slowly the inlet valve opens intermittently and sufficient time elapses between successive openings for the fuel to be carried into K and to be thoroughly vaporized

70

therein.

What I claim is:

1. A vaporizer for a multicylinder internal combustion engine having external carbureting means, comprising a mixture entrance, an inlet manifold in the form of a loop, comprising an upper portion with which said mixture entrance communicates, a substantially horizontal lower portion into which liquid fuel is adapted to drain by gravity and in which the fuel mixture will oscillate, an exhaust manifold in heat relation with the lower portion of said manifold for vaporizing the fuel therein, a plurality of mixture outlets from said loop manifold located below said mixture entrance and above said heating passage.

75

2. In an internal combustion engine, the combination of a manifold having an intake portion, means for arresting the unvaporized fuel oil particles at each of the entrances into the cylinders, and a trap for catching the heavy particles of fuel oil that are dropped from the mixture passing through the intake portion, said trap communicating with the said intake portion immediately at the entrance into the cylinders and only at opposite ends of the trap, said trap arranged to utilize the heat of the exhaust gases along substantially its entire length.

85

3. A manifold, comprising a single casting forming above an intake manifold, provided with discharge ends for delivering a mixture into the cylinder block, and below an exhaust manifold having a plurality of exhaust inlets for communicating with the engine block, said casting provided with a cored out passage having only its ends communicating with the two discharge ends of the intake manifold portion and having the

95

100

105

110

main portion closed off from the intake manifold and lying along the main portion of the exhaust passage whereby the heavy particles

5 of mixture passing through the intake manifold are caught and collected in the said trap where they are vaporized by the heat of the gases.

4. A manifold, comprising a casting forming an intake manifold provided with discharge ends for delivering a mixture into the cylinder block, and baffle means located in said discharge ends immediately at the entrances into the cylinder, and a closed trap member communicating with said discharge ends on the side of the baffle means remote from the cylinder block, and a main ex-

haust conduit in which said trap is located directly in the line of the exhaust from the engine.

5. In an internal combustion engine, a casting forming a lower exhaust manifold having ports for connection with the cylinder block, and an upper manifold having downwardly extending portions ending in ports for connection with the cylinder block, the said exhaust manifold having an additional closed passage cored in its upper side, and opening only into the intake manifold below the cylinder ports.

In testimony whereof I affix my signature.

GEORGE R. WELCH.
